UNITED STATES PATENT OFFICE.

FRED WEBORG, OF JAMESTOWN, NEW YORK.

FURNITURE-SPRING.

No. 833,012.

Specification of Letters Patent.

Patented Oct. 9, 1906.

Application filed October 18, 1905. Serial No. 283,296.

To all whom it may concern:

Be it known that I, FRED WEBORG, a citizen of the United States, residing at Jamestown, in the county of Chautauqua and State of New York, have invented a new and useful Furniture-Spring, of which the following is a specification.

This invention relates to furniture-springs, such as are used on buggy-seats, chair-bottoms, spring-sofas, bed-bottoms, and the like, and has for its object to provide a simple, inexpensive, and efficient device of this character in which the construction and general arrangement of the several parts are such as to render the spring strong, durable, and practically noiseless.

A further object of the invention is to provide a spring-frame constructed of a plurality of double helical springs having their terminal and intermediate whirls or convolutions connected by strips of wire fabric.

A still further object is to provide novel means for clamping the strips of wire fabric between the reduced intermediate convolutions of the springs and means for securing the terminal convolutions to each other and to the adjacent strip of wire fabric.

With these and other objects in view the invention consists in the construction and novel combination and arrangement of parts hereinafter fully described, illustrated in the accompanying drawings, and pointed out in the claims hereto appended, it being understood that various changes in form, proportion, and minor details of construction may be resorted to without departing from the principle or sacrificing any of the advantages of this invention.

In the accompanying drawings, forming a part of this specification, Figure 1 is a top plan view of a spring-frame constructed in accordance with my invention. Fig. 2 is a transverse sectional view taken on the line 2-2 of Fig. 1. Fig. 3 is an enlarged sectional view showing the manner of clamping the woven-wire strands between the convolutions or whirls at the reduced necks of the spring. Fig. 4 is a longitudinal sectional view of one of the auxiliary clamps or clips. Fig. 5 is a bottom plan view of the same, and Fig. 6 is a detail perspective view of one of the clamping members detached.

Similar numerals of reference indicate corresponding parts in all of the figures of the drawings.

The improved device consists of a pair of spaced substantially rectangular frames 5 and 6, between which are mounted a plurality of double helical springs 7, the terminal convolutions of which are fastened to the frames in any suitable manner, as by clips 8. Extending longitudinally of the frames 5 and 6 and connecting the necks of the springs 7 are strips of woven-wire fabric 9, which pass between the reduced convolutions or whirls 9' of the spring at said necks and serve to retain the several springs in their relative position and at the same time reinforce and strengthen the same. The springs 7 are also connected by transverse strips 10, the opposite ends of which pass between the reduced convolutions of the coils and beneath the strips 9, being retained in engagement therewith by the spring-clamping action of said coils.

As a means for preventing accidental displacement of the strips 9 and 10 suitable U-shaped clamping members 11 are provided, the spaced arms of which are preferably pointed, as indicated at 12, while the connected ends of the arms are bent upwardly to form loops or handles 13, adapted to engage the interior walls of the reduced convolutions when in position on the springs 7, as clearly shown in Figs. 1 and 3 of the drawings. The pointed ends of the members 11 are threaded through the wire fabric 9 and 10 and are preferably disposed one above and the other below the central portions of the springs, with their loops or handles 13 arranged at right angles to each other and in contact with the adjacent convolutions or whirls, as shown, so that the fabric will be securely retained in position. The springs 7 are also preferably connected by short chains 14, and extending longitudinally and centrally of the frames 5 and 6 are strips of wire fabric 15, which are secured to the terminal convolutions of the springs by clips 16, the opposite ends of which embrace said convolutions and are formed with terminal inwardly-extending teeth or spurs 17, adapted to engage the wire fabric 15. It will thus be seen that the springs are securely fastened to the spaced supporting-frames and to each other and by reason of the flexible connecting-strips will permit the springs to readily yield under pressure and return to normal position as soon as the pressure is removed. It will also be observed that the longitudinal

and transverse strips of wire fabric are held in position on the springs by the clamping action of the reduced convolution and also by the clamping members or U-shaped pins, 5 thereby effectually preventing accidental displacement of said fabric.

Having thus described the invention, what is claimed is—

1. In a device of the class described, a plurality of springs secured together by longitudinal and transverse flexible connections, and clamping members carried by the springs and provided with spaced arms adapted to pierce the flexible connections.
- 15 2. In a device of the class described, a plurality of springs, longitudinal and transverse flexible connections interposed between the convolutions of the springs and disposed in contact with each other, and clamping members carried by the springs and provided with arms adapted to pierce the flexible connections.
- 25 3. In a device of the class described, a plurality of springs, longitudinal and transverse woven-wire connecting-strips interposed between the convolutions of the springs, and clamping members engaging the interior walls of the convolutions and provided with spaced arms adapted to pierce the wire mesh of the connecting-strips.
- 30 4. In a device of the class described, a plurality of double helical springs secured together at their reduced central convolutions by flexible connections, and clamping members disposed within the reduced convolutions and provided with spaced arms adapted to pierce the flexible connections.
- 35 5. In a device of the class described, a plurality of double helical springs secured together at their reduced central convolutions by flexible connecting-strips, and clamping members disposed within the reduced con-

volutions and piercing the connecting-strips, said clamping members being arranged at right angles to each other.

6. In a device of the class described, a pair of spaced frames, a plurality of springs secured to the frames, flexible longitudinal and transverse connecting-strips interposed between the central convolutions of the 50 springs, clamping members carried by the springs and piercing the connecting-strips, and a flexible strip extending longitudinally of each frame and connected to the terminal convolutions of the springs.

7. In a device of the class described, a pair of spaced frames, a plurality of double helical springs having their terminal convolutions secured to the frames, flexible longitudinal and transverse connecting-strips interposed between the reduced central convolutions of the springs, clamping members disposed within the reduced convolutions and piercing the connecting-strips, a flexible strip extending longitudinally of each frame, 65 and clips embracing the terminal convolutions of the springs and provided with teeth for engagement with the longitudinal strip.

8. In a device of the class described, a plurality of springs, longitudinal and transverse connecting-strips interposed between the convolutions of the springs, and a substantially U-shaped clamping member having its closed end bent upwardly for engagement with the interior walls of the convolutions 70 and its open end piercing the connecting-strips.

In testimony that I claim the foregoing as my own I have hereto affixed my signature in the presence of two witnesses.
